STAMP HOLDER

William Betz, Elizabeth, N. J.

Application October 1, 1938, Serial No. 232,862

3 Claims. (Cl. 81—43)

This application is a continuation in part of my pending application filed February 20, 1937, Serial Number 126,936, Patent No. 2,157,226, dated May 9, 1939.

5 My invention relates to a stamp holder of a type which may be employed for gripping a stamp or similar sheet for the purpose of inspection, or otherwise, and it consists in the constructions, arrangements and combinations 10 herein described and claimed.

It is the cardinal purpose of the invention to provide a holder in the form of a pair of tweezers and in which a gravity-actuated means secures the gripping fingers upon the stamp or sheet.

15 It is a further object of the invention to provide a structure of extreme simplicity in construction and assembly.

Additional objects, advantages and features of invention will be apparent from the following description and accompanying drawing, wherein

20 Figure 1 is a longitudinal sectional view of the holder.

Figure 2 is a fragmentary longitudinal sectional view of the device in open position.

25 Figure 3 is a similar view of the device in closed position.

Figure 4 is a cross section on the line 4—4 of Figure 3.

30 There is illustrated a holding device, generally indicated at 10 which comprises a pair of gripping fingers or arms 11, arranged in parallel relation and abutting each other at one end, where they are secured by a small bolt or rivet 12, the free ends of the arms 11 terminating in flat broadened jaws 13, for a purpose, as will presently appear.

35 Each of the arms 11 are slightly bowed, and normally assume a position spaced from each other at their free ends. Intermediate the lengths of the arms 11, a slot 14 is formed extending longitudinally thereof and diametrically opposite each other, and slidably mounted in these slots there is a locking means 15, as will now be described. The catch members 15' of the locking means are formed from an elongated blank of metal, slotted at spaced intervals, then bent so as to have a spherical contour longitudinally of the blank, and the longitudinal edges of the blank then bent to define flanges 16, permitting ready securement within the slots of the arms 11. Thus, there are provided a series of loop members 17 spaced longitudinally of the blank. The loops 17 of the catches are spaced or offset with respect to the loops of the other catch member so that the loops may be interleaved, as clearly shown in Figures 2 and 3. The loops 17 are progressively shorter in length in the direction of the secured ends of the arms, as may be

seen in Figures 2 and 3. A ball 18 is housed in one of the catch members 15' and is freely movable longitudinally through the loops of the catch. The uppermost and lowermost loops 17 of the catches 15' are spaced sufficiently close to the 5 edges of the slot 14 to retain the ball. However, it should be noted that the clearance between the loops and the slot is such as to permit movement of the ball, during interleaving of the loops, and it will be apparent that as the ball moves 10 away from the gripping ends of the arms, it will encounter the progressively shorter loops which will prevent exit of the ball from within the loops. The slots 14 of the arms 11 extend beyond the outermost loops for accommodation of the ball, 15 as may be seen in Figure 2.

In use, it is only necessary to compress and point the arms 11 upwardly when the ball 18 will roll toward the fastened end and lock the arms against separation; and to release the arms, they 20 are compressed and pointed downwardly, allowing the ball to roll toward the free ends of the arms and release the arms.

While I have described the device as a stamp holder, it will be apparent that it is susceptible to 25 use as an ordinary tweezers, and while a preferred form has been shown and described, I consider as my own all such variations in construction as fairly fall within the scope of the appended claims.

I claim:

1. A device of the character described comprising a pair of spring arm members arranged in parallel relation connected at one end, means connecting the arm members comprising spaced loop members, the loops of one arm member adapted to interleave with loops of the other arm member, the loops being progressively shorter in length in the direction of the connected end of the arm members and a retainer member movable through the interleaved loops.

2. A device of the character described comprising a pair of bowed spring arm members arranged in parallel relation and connected at one end, each of the arms having a slot intermediate their length, a catch member seated in each slot, said catch members having looped portions spaced for interleaving relation with each other and a member within one of the catch members movable through the looped portions when interleaved, the looped portions being progressively shorter in length in the direction of the connected ends of the arms.

3. The structure of claim 2 in which the looped portions adjacent the ends of the slots stop short 55 thereof.

WILLIAM BETZ.
